SYNCHRONOUS CIRCUIT MAKE AND BREAK DEVICE

Walter E. Palmer, Cicero, Ill.

Application September 10, 1937, Serial No. 163,232

11 Claims. (Cl. 200—91)

It is well known that in making and breaking an electric circuit, considerable arcing of the current is occasioned at the make and break points which eventually causes considerable damage, and is objectionable for many reasons. These 5 arcings are occasioned by reason of the fact that the making and breaking has heretofore been effected, especially in alternating current, when the current is pulsating or flowing, and the higher 10 the voltage on the line the greater will be the arc. It is one of the objects of the present invention to provide an improved make and break device by means of the use of which an alternating circuit will be made and broken at the neutral point 15 in the sine wave of the current, or when there is no current flowing, and to that end the invention consists in providing an improved circuit make and break device, embodying in its construction a motor operating in synchronism with the current in the line which is to be controlled, whereby 20 the circuit will be made and broken when the current value is zero, or between alternations of this current.

To the attainment of these ends and the accomplishment of other new and useful objects as will appear, the invention consists in the features of novelty in substantially the construction, combination and arrangement of the several parts hereinafter more fully described and claimed and 30 shown in the accompanying drawings illustrating this invention, and in which

Figure 1 is a side elevation of a device of this character constructed in accordance with the principles of this invention.

Figure 2 is a sectional view taken on line 2—2, Figure 1, with parts omitted.

Figure 3 is a horizontal sectional view taken on line 3—3, Figure 1, with parts omitted, and on an enlarged scale.

Figure 4 is a sectional view taken on line 4—4, Figure 3, with parts omitted.

Figure 5 is a detail sectional view taken on line 5—5, Figure 3.

Figure 6 is a view partly in section as taken on line 6—6, Figure 3, showing in diagram the wiring.

Referring more particularly to the drawings, the numeral 10 designates a shaft which is journaled in suitable bearings such as in supports 11 held in position in any suitable manner. A drum 12 50 constructed of any suitable insulating material and having contact plates 13—14 recessed into the periphery thereof, is mounted for free movement on the shaft 10.

Adjacent the end of the drum 12 is arranged 55 a disc 16 having a cut away portion 17 and a

cut away portion 18 to form a shoulder 19. Encompassing the shaft 10 is a coiled spring 20 one end of which rests against a lug 21 on the disc 16 and the other end of the spring rests against a projection 23, which is secured to the end of the drum 12 and is disposed in the space or cut away portion 17 of the disc 16. The disc 16 is secured to the shaft 10 by a set screw 15.

Passing through the shoulder 19 is a screw 24 one end of which contacts the support 23 so that by adjusting the screw 24 a rotary adjustment of the drum relative to the shaft 10 may be obtained.

If desired, a lock nut 25 may be provided for locking the screw 24 against adjustment.

Carried by a suitable support 26 are contact brushes 27 one for each of the contact plates 13—14 on the drum 12, and are disposed to engage the periphery of the drum 12 as well as the contact plates 14. These brushes may be held in position in any suitable manner but preferably by means of upright pins or members 28 which are preferably screw-threaded and are provided with nuts 29 to form binding posts to which one of the terminals 30 of the line which is to be controlled is connected.

If desired, one or more springs 31 may be provided which tend to hold the brushes 27 in contact with the periphery of the drum. These springs contact the support 26 and also an insulating cross-bar member 32 which latter is adjustably secured in position by means of bolts 33 as shown more clearly in Figures 1 and 4.

The brushes 27 are preferably provided with inclined faces 34 into which are recessed rollers 35 or balls 35. A spring pressed plunger 36 contacts with one of the rollers or balls 35 and a conical member 37 contacts the other of the rollers or balls 35. This conical member 37 preferably forms an extension on a screw or bolt 38 threaded into the support 26 and held against adjustment by means of a nut or collar 39.

The upright 28 forming a part of the binding post preferably passes through a slot 40 so as to permit the brushes 27 to be moved laterally for a limited distance and whenever individual adjustment is necessary or desired. The spring pressed plunger 36 contacting the ball 35 tends to move the brush 27 towards the right in Figure 4, and by adjusting the conical member 37 upwardly the brush 27 will thus be moved to the right. However, when the adjustment to the left in Figure 4 is desired for the brush 27, the conical member 37 is forced downwardly and the spring 55

pressed plunger 36 will yield sufficiently to permit the brush to so move.

Another brush 41 similar to the brush 27 and similarly adjusted also contacts the periphery of the drum 12 and is in position to be engaged by the contact members 14 carried by the drum. These members 14 are of such a length that they will span the space between the brushes 27 and 41 when the drum is moving in the direction 10 of the arrow in Figure 4 at the points where the make and break of the circuit is effected.

To the binding post 42 which is connected to the brush 41 is secured the other terminal 43 of the line or circuit which is to be controlled.

16 Thus it will be seen that when the drum 12 is rotated clockwise, the contact members 14 will engage or move out of engagement with the brushes 27-41 and thereby open or close the circuit in the controlled line.

20 The drum 12 by its rotation effects the make and break of the circuit and this drum is rotated intermittently by means of a synchronous motor 44.

To that end there is provided on the shaft 45 of the motor 44 a gear 46 of any suitable type, preferably a spiral gear which meshes with a spiral gear 47 that is mounted upon and rotates freely about the shaft 10, and mounted upon the shaft 10 adjacent but spaced from the gear 47 is a disc 30 48, the disc being secured to the shaft for rotation therewith in any suitable manner such as by means of a set screw 49.

Secured to and projecting laterally from the gear 47 and disposed in the space between the gear 47 and the disc 48 is a collar 50 which rotates with the gear 47 and in a counter-clockwise direction as shown more clearly in Figure 6. This collar 50 is provided with a shoulder 51 for a purpose to be set forth. Carried by the disc 48 is a dog 52 which is pivotally mounted thereto and intermediate its ends as at 53, and is provided at one extremity with a shoulder 54. A second shoulder 55 is provided on the dog 52 and this shoulder 55 is adapted to be moved into and out 45 of the path of the rotary movement of the shoulder 51 on the collar 50, so as to lock the disc 48 for rotation with the gear 47 and with it the shaft 10 for rotating the drum 12. When the shoulder 55 is moved out of engagement with the shoulder 51 the disc 48 will be arrested in its rotation by means of another dog 56, the operation 50 of which latter will be presently described.

A spring 57 is provided for moving the dog 52 into an operative position with respect to the shoulder 51. One end of this spring is anchored 55 as at 58 to the dog 52 and at 59 to the disc 48. A stop pin 60 carried by the disc 48 is provided for limiting the movement of the dog 52 about its pivot in a direction to cause the shoulder 55 to 60 disengage or move out of the path of rotation of the shoulder 51 on the collar 50.

Thus it will be seen that when the dog 52 is in the position shown in Figure 6 the disc 48 will be held against rotation by the dog 56 entering one 65 of the notches or seats 61 in the periphery of the disc 48. In this position of the dog 52 the collar will rotate freely with the gear 47 but the drum 12 will remain still. When, however, the dog 52 is moved into a position that it will contact the shoulder 51, then the disc 48 will be locked to the shaft 10 for rotation therewith, and as the disc 48 is secured to the shaft 10 of the drum 12 for rotation therewith, the drum will be correspond- 70 ingly rotated and the contact points 14 on the

drum will be moved into and out of engagement with the respective brushes 41-27.

Upon each operation of the disc 48 as well as the drum 12, they will move one-half of a revolution, or 180°, at which time the dog 52 will be shifted to cause the shoulder 55 to disengage the shoulder 51 and the end of the dog 56 will drop into one of the notches or seats 61 in the periphery of the disc 48 to hold the latter under tension and the end 54 of the dog 52 against a stop shoulder 70 or 78 to be later described.

In order therefore to effect this operation it is necessary to control the operation of the dog 52.

In the present exemplification of this invention mechanism is shown for controlling the dog 52 to effect a making or closing of the circuit which is to be controlled, and also mechanism is shown to effect the breaking of the circuit.

The control mechanisms, however, are arranged at different points in the cycle of operation of the dog.

The dog 56 is pivotally mounted as at 62 and a spring 63 one end of which is anchored to the dog as at 64 and the other end being anchored to a support 65 tends normally to move the end of 25 the dog 56 in a direction to enter one of the seats 61 when the latter is in a position to receive such an end.

An electroresponsive device preferably in the form of a magnet 66 and embodying a coil 67 has 30 co-operating therewith an armature 68 pivotally supported intermediate its ends as at 69, and is provided with a shoulder 70. This shoulder is adapted, when the armature 68 moves about its pivot in one direction to assume a position in the path of movement of the shoulder 54 of the dog 52 when the disc 48 is rotated, and when the shoulder 54 contacts the shoulder 70 the dog 52 will be rocked about its pivot 53 against the stress of the spring 57 so as to move the shoulder 55 40 45 out of engagement with the shoulder 51 and thereby release or unlock the disc 48 with respect to the gear 47 so that although the gear 47 may be further rotated the movement of the disc 48 as well as the drum 12 will be arrested.

At this time the dog 56 will enter the notch 61 in the disc 48. The parts will remain in this position until the magnetic or electroresponsive device is energized, to attract the armature 68 to swing it about its pivot 69 and thereby move the shoulder 70 out of engagement with the shoulder 54 on the dog 52, allowing the latter under the stress of the spring 57 to assume a position in the path of movement of the shoulder 51 on the collar 50 to again lock the disc 48 and the drum 12 for rotation with the gear 47.

Arranged in proximity to the electroresponsive device 66 is another electroresponsive device 71 embodying a coil 72. Co-operating with this electroresponsive device 72 is an armature 73 which is pivotally supported intermediate its ends as at 74 and provided on one end of the armature 73 is a shoulder or stop 75 with which a shoulder 76 on the end of the armature 68 is adapted to co-operate. A coiled spring 77 is anchored by one 65 end as at 78 to the end of the armature 68 and is anchored as at 79 to the end 80 of the armature 73.

The shoulder 75, at a predetermined time in the cycle of operation of the device, assumes a position with respect to the shoulder 76 or the armature 68, so as to lock the latter against operation and prevent the armature 68 from moving about its pivot 69. This will prevent the movement of the shoulder 70 away from the path of movement 75

of the shoulder 54 on the dog 52, with the result that the disc 48 and the drum 12 will not be disturbed in their positions even though the magnet 66 were at that instant energized.

5 However, when the parts are in the position shown in full lines in Figure 6 the energization of the electroresponsive device 66 will cause the armature 68 to swing about its pivot to release the dog 52; this happens when the coil 67 is de-energized and the spring 77 moves the armature 68 into the position shown in Figure 6.

10 Should the coil 72 be energized when the shoulder 70 of the armature 68 is in engagement with the shoulder 54 of the dog 52, the shoulder 75 on the armature 73 will be moved into engagement with the shoulder 76 on the armature 68 and lock the latter in such a position.

15 Thus it will be seen that when the coil 67 and the coil 72 are both energized, the dog 52 will not be released since the contacting shoulders 75 and 76 respectively of the armatures 73 and 68 will lock the latter against movement. When the dog 56 is moved out of the notch or seat 61 a projecting portion 81 thereof will serve to 20 close a make and break device embodying spring arms 82 and 83 for a purpose to be later described.

25 The coil 84 together with a coil or electroresponsive device 85 correspond respectively with the coil or electroresponsive device 67-72 arranged on opposite sides of the mechanisms. The coils 67-72 co-operate to effect what might be termed the "off" position while the coils 84-85 co-operate to effect what might be termed the "on" position.

30 The synchronous motor 44 is provided with an inductive or starting winding 86 and a synchronous winding 87 and on the motor shaft, and in the circuit of the inductive winding two centrifugal switches 88-89 are provided.

35 The switch construction which controls the operation of the device embodies an intermediate spring member or finger 90 and spring members 91-92 on opposite sides of the member 90, and a switch button or knob 93 being provided 40 for the operation of this switch construction. It will be noted that upon the first depression of the button 93 electrical contact will be made between the members 92 and 90 of the switch structure. This connection, as will be later described, starts the motor into operation and locks both the "on" and "off" release mechanisms. A further depression of the button 93, and while the member 92 is in contact with the member 90, will move the member 90 into electrical contact with the member 91 and this will energize the respective electroresponsive devices.

45 The motor operates in synchronism with the sine wave or pulsations in the circuit, and one adjustment may be effected by means of the structure shown in Figure 5, that is, by means of the adjustment of the disc 16 with respect to the drum, through the medium of the screw 24 working through the shoulder 19 and against the support 23 carried by the drum 12, the disc 16 being fast on the shaft by means of the screw 15, while a finer individual adjustment may be obtained by the adjustment of the conical elements or members 37 operating upon the brushes 27, shown more clearly in Figure 4.

50 A centrifugal switch 88 operates to automatically cut out the inductive winding 86 from the line after synchronism of the motor with the alternations or pulsations in the line has been obtained.

55 The centrifugal switch 88 operates to cut out

the local inductive circuit which would otherwise pass through the lock coils in series, to-wit: the coils 72 and 85 that would return to the inductive winding and which would complete a secondary circuit that would otherwise operate the lock coils 72-85 contrary to the intention of the desired operation.

60 Obviously the breaker drum 12 may be geared to obtain any desired degree of ratio of rotation between the motor and the breaker drum.

65 When the motor is started by depressing the button 93, so as to form an electrical connection between the members 92 and 90 of the manual control switch, both the centrifugal switches or cut outs 88-89 are closed, allowing the current to pass through both the inductive and synchronous windings 86-87. These switches or cut outs 88-89 remain closed until the motor has attained synchronism with the current sine waves or alternations in the supply 20 line of the controlling circuit. At this time in the cycle of operation of the device, both of the switches or cut outs 88-89 open, thereby cutting off current from the inductive winding 86 and lock coils 72-85, thus allowing the motor 25 to run on the synchronous winding only, and simultaneously de-energizing the lock coils.

70 When the button 93 is depressed so as to move the member 92 into electrical connection with the member 90 the current will flow as follows:

75 From line 94, to conductor 95, contact 90, contact 92, conductor 96, conductor 97, at which point the current will divide, a portion thereof flowing through the switch 89, inductive winding 86, conductor 98, conductor 99 to the other side 35 of the line 100, thus energizing the inductive winding 86 starting the motor.

80 The other portion of the current will flow from the conductor 97 to conductor 101, through synchronous winding 87 to the line 100, thereby 40 enabling the synchronous winding to control the speed of the motor when such speed has been obtained.

85 After the current has passed through the switch 89, a portion thereof will flow through the conductor 105, to coil 72, conductor 104, coil 85, conductor 103, to switch 88, to conductor 102, conductor 99 back to the line 100. This 50 circuit will continue to flow thereby locking the coils 72 and 85 until such time as the motor has attained synchronous speed, when switch 88 automatically opens to cut off this last referred-to circuit, thereby releasing the locks 72 and 85.

90 Then the button 93 is further moved to cause the member 90 of the switch to also be moved into electrical contact with the member 91 of the switch. In this position the current will flow from the line 94 through conductor 95, member 90, member 91, conductor 106, coil 67 out through conductor 107, conductor 108, back to 60 the conductor 100 on the other side of the line, thereby actuating the "off" release 67, provided motor has attained synchronous speed, opening switch 88 and releasing lock 72.

95 The sequence of operations taking place upon 65 the depression of the "off" button 93 are as follows:

Upon bringing the contact members 92 and 90 into engagement the motor is started by the current flowing through the inductive or starting 70 winding, and simultaneously the lock coils 72 and 85 are energized to lock the armatures 68 and 69-A in their positions.

Upon further depression of the key or button 93, the members 90 and 91 are connected and 75

magnet 67 will be energized tending to pull the armature 68 and shoulder 70 to release the dog 52 to permit the latter to assume a position where it will engage the rotating shoulder 51; but this is prevented by the locking shoulder 75 held by the energized locking magnet 72. However, as soon as the motor attains synchronous speed, the locking magnets are de-energized by the automatic opening of the centrifugal switches 88-89, and the locking shoulder 75 is moved out of engagement with the shoulder 76, thereby allowing the armature 68 to be attracted by the magnet 67 to release the dog 52 into engagement with the rotating shoulder 51, and thereby im- 10 part to the disc 48, and through it to the shaft 10, a rotary motion in the direction of the arrow shown in Figure 6.

Upon the initial movement of the disc 48, the dog 56 is raised from the notch 61 of the disc 48, and thereby the switch members 82-83 are brought into contact.

As soon as this takes place, the windings of the motor will be maintained in line connection, even though the pressure from the "off" button 93 is entirely removed, which would cause all of the members 92-90-91 to move out of electrical contact; thus the function of the switch 82-83 is to insure the completion of the cycles of operation initiated by the depression of the 30 "off" key 93.

The motion of the disc 48 continues for one-half of a revolution, when the shoulder 54 will be engaged by the shoulder 70-A of the armature lever 68-A, and the dog 52 will be dis- 35 engaged from the rotating shoulder 51. At this point the contact 56 will engage the second notch 61 and thereby lock the disc in its "off" position and simultaneously separate the switch arms 82-83, thus opening the motor circuit.

At the completion of these functions, the contact member 14 will rest opposite and out of engagement with the brushes 21 and 41, as shown in dotted lines in Figure 4.

An examination of Figure 4 indicates that the break in the control circuit can only occur when the point "B" on the contact 14 has reached the point "B-1" on the shoe 21. Otherwise a make, (that is, a completion of the circuit) can only occur when the point "M" on the contact 14 has reached the point "M-1" on the shoe 41, upon a further rotation of the drum 12 in the same direction, and after the insert 14 has once passed out of engagement with the shoes 21 and 41. This involves a time interval between the moment when the drum 12 is placed in motion and the instant or instants when the current value is zero.

Another conductor 107-A leads from the coil 84 and is connected to the switch member 91-A of the "on" button 93-A so that the coil 84 may be energized when the button 93-A is depressed for the actuation of the armature 68-A.

In this position of the parts of the switch and when the motor has attained synchronism with the alternations in the line 94-90, the switch 89 will automatically open, thereby cutting out the starting winding 86 and this will de-energize the coil 72 with the result that the spring 71 will move the armature 73 to the full line position shown in Figure 6. That is, so that the shoulder 75 will be moved to a position out of engagement with the shoulder 76 on the armature 68. The coil 67 being then energized will attract the armature 68, moving the shoulder 70 out of contact with the shoulder 54 on the dog 52, releas-

ing the latter, allowing the spring 57 to swing the dog 52 about its pivot so that the shoulder 55 will engage the shoulder 51 on the collar 50 and thereby lock the disc 48 for rotation with the gear 47.

While the members 92, 90 and 91 of the switch are in electrical contact, current will also flow through the conductor 96, to the switch member 83. As the disc 48 rotates, the dog 56 will be unseated from the notch or seat 61 causing the dog 56 to swing about its pivot 62 against the stress of the spring 63, with the result that the projecting portion 81 on the dog 56 will engage the contact arm 82 and close the switch, by moving the member 82 into engagement with the member 83 so that the current flowing in through the conductor 96 and switch member 83 will then continue to flow through the switch member 82, conductor 108, back to the conductor 94 on the other side of the main supply line.

Thus it will be seen that by pressing the button 93 the motor will first be started on the inductive or starting winding 86, and the coil 72 will be energized to move the armature 73 to a position that the armature 68 will be locked against movement about its pivot 69, and the dog 52 will be maintained in a position that the disc 48 will remain idle but the motor will continue to run.

When the motor has attained synchronism with the pulsations in the main line, and upon a further depression of the button 93 so as to cause the members 92, 90 and 91 to be all in electrical contact, current will flow through coil 67 to energize it with the result that the armature 68 will be attracted and the shoulder 70 will be moved out of engagement with the shoulder 54 to release the dog 52 to cause the disc 48 to be locked with the gear. The disc will then rotate and the dog 56 will move the contact members 82-83 into engagement, thereby closing the circuit causing the motor to continue to run until the disc has assumed the position that another one of the seats 61 will be positioned to receive the dog 56. Just previous to this movement of the dog 56 the coil 67 becomes deenergized, and the spring 71 will move the armature 68-A on the opposite side of the line into a position that the shoulder 54 of the dog 52 will engage a shoulder 70-A on the armature 68-A, so that the dog 52 will be shifted to release the disc 48 with respect to the gear 47. Just at this time one of the seats or recesses 61 will be in a position to receive the dog 56.

It is of course to be understood that to perform the opposite operation, that is, what might be termed the "on" position, the other button 93-A which controls the coils 84 and 85 must be operated, when the same sequence of events occur, culminating in the operation of the "on" actuating coil.

The coils 67-84 are respectively locked by the coils 72 and 85 until the motor attains synchronous speed, thus preventing operation of this device prior to the moment when the motor has attained such synchronous speed thereby insuring operation of the making and breaking of the controlled current when the current value is at zero or neutral point, i. e., when no current is flowing through the line.

When the coil 67 is first energized it will have no effect upon its armature 68 until the coil 72 is de-energized through the opening of the centrifugal switches 88-89, and when the coil 72 is de-energized, its armature 73 will assume a posi-

tion to permit the armature 68 to be attracted or moved by its controlling coil 67.

The switch device embodying the elements 82-83 is provided for the purpose of maintaining the motor in operation until the full throw of the drum 12 has occurred, regardless of whether either of the switch buttons 93-A is closed or open.

Obviously the device may be geared for the desired ratio of rotation between the motor 44 and the drum 12.

It is thought that the operation will be clearly understood from the foregoing, but briefly stated, it is as follows:

In Figure 4 the circuit breaker is shown in what might be termed a closed position, and the operation of the device will be described in connection with the left hand portion of the wiring diagram shown in Figure 6 embodying the coils 67 and 72.

To open the controlled switch, the left hand button 93 is depressed until the member 92 comes into contact with the intermediate member 90. This allows the current to flow from the controlling circuit through the motor winding and the coils 12-84 in parallel back to the other side of the line.

The motor starts on the inductive or starting winding 86, and when synchronous speed has been obtained, the coils 12-85 are de-energized through the opening of the centrifugal switches 89-88, thus allowing the actuating mechanism to operate, which occurs upon the movement of the intermediate member 90 of the switch into electrical contact with the member 91 of the switch.

It will be seen that the member 91 of the switch is connected with the coils 67, which latter when energized attracts the armature 68, allowing the shoulder 55 on the dog 52 to engage the shoulder 51 on the collar 50. The collar 50 then turns with the revolution of the motor 44, being fastened to the gear 47 for rotation therewith and which gear 47 is on the motor shaft. Thus when the shoulder 55 of the dog 52 engages the shoulder 51 on the collar 50, the dog 52 together with the disc 48 on which it is mounted is revolved in a counter-clockwise direction for one-half turn until the shoulder 54 on the dog 52 engages the shoulder 70-A on the armature 68-A that is controlled by the coil 84, as shown in Figure 6. The engagement of the shoulder 54 with the shoulder 70-A will swing the dog 52 about its pivot 53 against the stress of the spring 57 to cause the shoulder 55 to move out of engagement with the shoulder 51 on the collar 50.

In either position, that is, whether the circuit make and break device is at rest in what might be termed the "on" or "off" position, the dog 52 will engage in one of the seats or recesses 61 in the disc 48 for the purpose of holding the drum in such position. The dog 52 also acts to hold the points 54 and 70, or 54 and 70-A according to the position of the disc 48, under tension, that is, the end of the dog 52 will be held firmly against the stop 70 or 70-A. The tension of the spring 63 is preferably greater than the tension of the spring 57, for the reason that the spring 57 would otherwise overcome the tension of spring 63 and tend to rotate the dog 52 about its pivot 53, which action would force the disc 48 to rotate in a counter-clockwise direction, which is not desired. Such counter-clockwise rotation would result in the spring 57 drawing or positioning the dog 52 so that the shoulder 55 would con-

tact shoulder 51, and thereby cause another rotation of the disc 48 in a clockwise direction, which is not desirable at that particular time in the cycle of operation of the disc.

Upon completion of the "off" cycle of operation, the drum 12 will stop and all of the coils will become de-energized.

To perform the opposite operation from that which is performed by the structure shown on the left hand side of Figure 6, and to employ the coils 84-85, all that is necessary is to depress the other button 93-A or what might be termed the "on" button, when the same sequence of events occurs, as with the operation of the button 93, culminating in the operation or activity of the coils 84-85.

If desired, a suitable closure or cover 109 may be provided for the entire mechanism, and this cover may be held in position or supported in any desired or suitable manner.

While the preferred form of the invention has been herein shown and described, it is to be understood that various changes may be made in the details of construction, and in the combination and arrangement of the various parts, within the scope of the claims, without departing from the spirit of this invention.

What is claimed as new is:

1. A rotary circuit make and break device, a synchronous motor connected with an alternating current circuit and from which motor said make and break device is normally disconnected, means embodying a shiftable connecting element for connecting said make and break device with the motor for rotation therewith, means operating automatically to shift said element to lock the make and break device and the motor for operation in unison in a manner that at the instant of the make or break the current value is zero, means also operating automatically, and at a different point in the cycle of rotation of the make and break device, to shift said element to unlock the make and break device from the motor, and means operating to maintain the motor in operation until the full throw of the make and break device has occurred.

2. A rotary circuit make and break device, a synchronous motor connected with an alternating current circuit and from which motor said make and break device is normally disconnected, means embodying a shiftable connecting element for connecting said make and break device with the motor, means operating automatically to shift said element to lock the make and break device and the motor for operation in unison in a manner that at the instant of the make or break the current value is zero, means also operating automatically, and at a different point in the cycle of rotation of the make and break device, to shift said element to unlock the make and break device from the motor, and means operating to maintain the motor in operation until the full throw of the make and break device has occurred, the last recited means embodying a supplemental circuit make and break device, responsive in its operation to the operation of a portion of the connecting means between the motor and the first recited make and break device.

3. A rotary make and break device, a motor connected to an alternating current and normally disconnected from said make and break device, connecting means for connecting the motor and make and break device for operation in unison, electroresponsive means for rendering the said connecting means active, electroresponsive

- means for rendering the said connecting means inactive, means for controlling the operation of the electroresponsive means, means operating automatically to cut out the starting winding of 5 the motor when the motor operates in synchronism with the alternating current wave, and means operating automatically to interrupt any local circuit which might be established through and between said electroresponsive means and 10 the starting winding of the motor.
4. A rotary electric circuit make and break device, a synchronous motor connected to an alternating current circuit and from which motor said make and break device is normally disconnected, a shouldered element connected with the 15 motor for rotation therewith, an intermittently rotatable element connected with the make and break device, a pivotally mounted element carried by said rotatable element and movable into and out of active engagement with said shouldered element to lock said make and break device for rotation with said rotatable element, electroresponsive devices for causing said pivotally mounted element to become active in a manner 20 that at the instant of the make or break the current value in said circuit is zero, and means whereby said electroresponsive devices may be controlled.
5. In combination, a rotary electric circuit 25 make and break device, a synchronous motor connected to an alternating current circuit and from which motor said make and break device is normally disconnected, a shouldered element connected with the motor for rotation therewith, an intermittently rotatable element connected with the make and break device, a pivotally mounted element carried by said rotatable element and movable into and out of active engagement with said shouldered element to lock said make and break device for rotation with said rotatable element, electroresponsive devices for causing said pivotally mounted element to become active in a manner 30 that at the instant of the make or break the current value in said circuit is zero, and means whereby said electroresponsive devices may be controlled.
6. A rotary electric circuit make and break device, a synchronous motor connected to an alternating current circuit and from which motor said make and break device is normally disconnected, a shouldered element connected with the 35 motor for rotation therewith, an intermittently rotatable element connected with the make and break device, a pivotally mounted element carried by said rotatable element and movable into and out of active engagement with said shouldered element to lock said make and break device for rotation with said rotatable element, electroresponsive devices for causing said pivotally mounted element to become active in a manner 40 that at the instant of the make or break the current value in said circuit is zero, and means whereby said electroresponsive devices may be controlled.
7. A rotary electric circuit make and break device, a synchronous motor connected to an alternating current circuit and from which motor said make and break device is normally disconnected, a shouldered element connected with the motor for rotation therewith, an intermittently rotatable element connected with the make and break device, a pivotally mounted element carried by said rotatable element and movable into and out of active engagement with said shouldered element to lock said make and break device for rotation with said rotatable element, electroresponsive devices for causing said pivotally mounted element to become active in a manner 45 that at the instant of the make or break the current value in said circuit is zero, and means whereby said electroresponsive devices may be controlled, and means for arresting said rotatable element against overthrow when the said pivotally mounted element is rendered inactive.
8. In a make and break device, a synchronous motor connected to an alternating current circuit, a rotatable contact carrying element normally disconnected from said motor, a rotatable dog carrying element connected with said contact carrying element for rotation therewith, means connected with the motor and with which means the dog co-operates to lock said element for rotation with the motor, electroresponsive devices, armatures individual to the electroresponsive devices and controlled thereby, means carried by the armatures to be moved into interlocking relation whereby one armature will be locked against 50 operation, the last said means also adapted to be moved out of interlocking relation to permit one of the armatures to be engaged by said dog to move the latter out of the position in which it would lock the contact carrying element for rotation with the motor, and means whereby said armatures will be actuated to render said dog active and inactive in a manner that at the instant of the make or break the value of the current in the line is zero.
9. A device of the character described embodying a synchronous motor connected to an alternating current, a rotatable member separate from the motor, a contact carried by said member, a pair of brushes co-operating with said contact, said brushes spaced from each other in the direction of rotation of said contact and for a distance less than the length of said contact, and means operating automatically to connect said member with the motor, in a manner that the contact will move out of engagement with 55 one of the brushes to break the circuit, and into engagement with the other brush to make the circuit at the instant or instants when the current value is zero.
10. A rotatable electric circuit make and break device for controlling the circuit of a synchronous motor connected to an alternating current circuit, said device embodying a shouldered element connected with the motor for rotation therewith, an intermittently rotatable element 60 connected with the make and break device, a locking element mounted upon and movable with and with respect to the last said element, electroresponsive means for shifting said locking element with respect to its support and into engagement with said shouldered element in a manner that at the instant of the make and break the current value will be zero, and electroresponsive means for moving said locking element out of active relation with respect to said shouldered element.
11. A rotatable electric circuit make and break device for controlling the circuit of a synchronous motor connected to an alternating current circuit, said device embodying a shouldered element 65

connected with the motor for rotation therewith, an intermittently rotatable element connected with the make and break device, a locking element mounted upon and movable with and with respect to the last said element, electroresponsive means for shifting said locking element with respect to its support and into engagement with said shouldered element in a manner that at the instant of the make and break the current value 10 will be zero, electroresponsive means for moving

said locking element out of active relation with respect to said shouldered element, and means for maintaining the motor in operation until a full throw of the make and break device has occurred, the last recited means embodying a supplemental 5 circuit make and break device rendered active by the engagement therewith of the said locking element when the latter is shifted out of engagement with said shouldered element.

WALTER E. PALMER. 10
